UNITED STATES PATENT OFFICE.

THOMAS BRADY, OF EAST ORANGE, NEW JERSEY.

CLOSING AND LATCHING MECHANISM FOR DOORS.

Application filed July 7, 1924. Serial No. 724,637.

To all whom it may concern:

Be it known that I, THOMAS BRADY, a citizen of the United States, and a resident of East Orange, county of Essex, and State of New Jersey, United States of America, have invented certain new and useful Improvements in Closing and Latching Mechanism for Doors, of which the following is a specification.

10 This invention relates to closure mechanism particularly adapted for use in connection with doors or closures for hoppers, such as are used on railway cars.

Closures, such as those identified, are subjected to great pressure and to severe usage and often become warped or distorted. For this reason, it is difficult to effect the closing and opening of the doors or gates. This will be evident when it is borne in mind that 20 such closures are used for the chutes of freight cars used for transporting coal and similar products. In order to manipulate certain closures of the type specified, it is necessary to use tools or bars in order to 25 force the door to closed position and to use a hammer or other tool to release the latch.

This invention has for its salient object to provide closure means of the type specified so constructed and arranged that the 30 door or gate can be easily and readily latched and unlatched and when closed, will be securely held in closed position.

Another object of the invention is to provide a device of the character specified that 35 will be self-contained and will require no extraneous tools or bars for its latching and unlatching.

Another object of the invention is to provide a device of the character specified having means automatically operable when the 40 door is closed for preventing accidental release of the door latching means.

Another object of the invention is to provide latching mechanism having means for 45 retaining the door in partially closed position during the final manipulation of the closing and latching means to swing the door to full closed position.

Another object of the invention is to provide door closing and latching means having leverage means for exerting a strong pull 50 on the bar during its closing movement.

Further objects of the invention will ap-

pear from the following specification taken in connection with the drawings, which form 55 a part of this application, and in which—

Fig. 1 is an elevational view showing a portion of a hopper, a gate or door for closing the hopper and means constructed in accordance with the invention for closing 60 and latching the door, the door being shown in closed position.

Fig. 2 is a view similar to Fig. 1, but showing the door unlatched and the door closing and latch mechanism swung to in- 65 operative position.

Fig. 3 is a view similar to Fig. 1, but showing the door in partially closed position.

Fig. 4 is an elevational view partly broken 70 away showing the arrangement of the closing and latching mechanism on a railway car hopper.

Fig. 5 is a detail sectional elevation taken substantially on line 5—5 of Fig. 1. 75

Figs. 6 and 7 are sectional elevations taken substantially on line 6—6 and 7—7 of Fig. 1.

Fig. 8 is an elevational view similar to Fig. 1, but showing a simpler form of latch- 80 ing mechanism.

Fig. 9 is a view similar to Fig. 1, but showing a slightly modified form of closing and latching means.

Fig. 10 is a view similar to Fig. 9, but 85 showing the door in partly closed position.

Fig. 11 is a view similar to Fig. 9, but showing the latching mechanism released and the door open.

Fig. 12 is a sectional elevation taken sub- 90 stantially on line 12—12 of Fig. 9, and

Fig. 13 is a view similar to Fig. 9, but showing a slightly different form of link.

The invention briefly described consists of 95 door closing and latching means comprising a bar pivoted on a fixed pivot and having pivoted thereto a second bar. The first named bar has a latching element adapted to latch the door in full closed position and the second bar has a latching element adapt- 100 ed to engage the door before it reaches full closed position. The bars are so relatively arranged and pivoted that a strong leverage can be obtained through the first bar to pull the door to closed position after the latching 105 element of the second bar has engaged the

door. Means is also provided for preventing accidental release of the latching means after the door has been closed and latched. Further details of the invention will appear from the following description.

Referring, first, to the embodiment of the invention shown in Figs. 1 to 7 inclusive there is illustrated a portion 10 of a hopper chute having a door or gate 11 hinged thereto at 12.

The door has an angle iron bar 13 secured thereto adjacent its lower end. The bar 13 extends laterally beyond the edge of the door as shown particularly at 14 in Figs. 6 and 7.

A bar 15 is pivoted at 16 to the wall of the chute 10. A latching pawl 17 is fixedly secured to the bar 15 in a position to engage the angle iron bar 14 and latch the door or gate in its full closed position shown in Fig. 1. The pawl 17 has its upper end offset or flanged as shown at 18 for reasons hereinafter described. (See Fig. 6.) A second latching member 19 is pivoted at 19' to the bar 15, and, as shown in Fig. 1, is adapted to extend under the angle iron bar 13 when the door is latched in closed position. The engagement of the latching member 19 with the under surface of the bar 13 prevents accidental release of the latching means.

An arm or bar 20 is pivoted at 21 to the bar 15 and attention is directed to the fact that the pivot 21 is disposed on the opposite side of the pivot 16 of the bar 15 from the latching elements 17 and 19. A pawl or tooth 22 is fixedly secured to the arm 20 in such a position that this pawl will engage the bar 13 as shown in Fig. 3 before the door reaches its full closed position.

An arm 23 is secured to the bar 15 and has a flanged lower end 24 adapted to limit the swinging movement of the arm 20 about its pivot 21 and to engage the free end of this arm and release the pawl 22 when the bar 15 is swung in a clockwise direction to release the door.

The upper end of the member 19 is offset as shown at 25 in Fig. 7 and this offset end can be engaged by the operator to release the latching element 19 from its latching position.

The structure just described operates as follows. The door or gate 11 is first swung to the position shown in Fig. 3 wherein the pawl 22 carried by the arm 20 will automatically engage over the bar 13, thus holding the door in partially closed position. When this position has been reached downward pressure on the free end of the bar 15 will exert a strong pull because of the leverage obtained upon the door and the door can be forced to its full closed position shown in Fig. 1. When the door reaches this position, the pawl 17 will drop into place over the bar 13 and the latching element 19 will

drop into place beneath the bar 13 thereby securely retaining the door in closed position. In order to release the door, the latching member 19 is first released by swinging this member in an anti-clockwise direction about its pivot 19'. Then the bar 15 is swung in a clockwise direction and the offset end 24 of the member 23 will engage and lift the arm 20 and pawl 22, thus releasing the door. The swinging movement of the bar 15 is limited by a stop 26 on the chute 10.

In the embodiment of the invention shown in Fig. 8, the bar 15 carries only the fixed latching pawl 17 and the latching element 19.

In the embodiment of the invention illustrated in Figs. 9 to 12 inclusive, the bar 35 is pivoted at 36 to the chute 10 and has secured thereto an arm 37 adapted to engage a channel iron bar 38 secured to the door 11 and extending laterally therefrom as shown at 39 in Fig. 12 when the door is in closed position as shown in Fig. 9.

A latching element 40 similar to the element 19 of the foregoing figures is pivoted at 41 to the bar 35 and has an offset upper end 42.

Instead of an arm such as the arm 20 in the embodiment of the invention shown in Figs. 1 to 7 inclusive, the bar 35 in this instance has pivoted thereto at 43 a link 44, 95 having a turn-buckle 45 therein. The free end of the turn-buckle carries a loop or ring 46 adapted to engage over the end 39 of the bar 38. A stop 47 on the chute 10 limits the swinging movement of the bar in an anti-clockwise direction as shown in Fig. 9 and this stop also limits the swinging movement in a clockwise direction as shown in Fig. 11.

The embodiment of the invention just described operates as follows. The door 11 is first swung to a position in which the loop or ring 46 can be engaged over the end 39 of the bar 38. The bar 35 is then swung about its pivot in an anti-clockwise direction, thereby bringing the door to its closed position and when this position has been reached, the arm 37 will engage over the end 39 of the bar 38 and the latch 40 will drop into position beneath this bar, thereby preventing any accidental release of the latch. This form of the invention enables the leverage to be exerted over a wider range than is possible with the form of the invention shown in Figs. 1 to 7 inclusive, and the length of the link 44 can be regulated by the turn-buckle 45. The only difference between the embodiment of the invention shown in Fig. 13 and that shown in Figs. 9 to 12 inclusive resides in the substitution of a chain 50 for the link 44.

From the foregoing specification it will be seen that simple and practical means has been provided for closing and latching doors or gates and that the use of this mechanism

enables the operator to exert a strong leverage, thereby facilitating the closing and latching of the door.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, a door movable to open and closed position and means for closing and latching said door comprising a bar pivoted on a stationary pivot, a latch fixed on said bar and adapted to engage the door in its closed position and a second latch pivoted to said bar and adapted to retain the bar and first named latch against accidental displacement after the door has been closed and latched.

2. In combination, a door movable to open and closed position and means for closing and latching said door comprising a bar pivoted on a stationary pivot, a latch fixed on said bar and adapted to engage the door in its closed position, and an arm pivoted on said bar and having a latching pawl engageable with the door when the door has been moved to partially closed position, the pivotal connection between said arm and bar being disposed on the opposite side of the bar pivot from the latch fixed thereon.

3. In combination, a door movable to open and closed position and means for closing and latching said door comprising a bar pivoted on a stationary pivot, a latch fixed on said bar and adapted to engage the door in its closed position, an arm pivoted on said bar and having a latching pawl engageable with the door when the door has been moved to partially closed position, the pivotal connection between said arm and bar being disposed on the opposite side of the bar pivot from the latch fixed thereon, and means pivoted to said bar and adapted to retain the latching means in operative position and against accidental displacement.

4. In combination, a door movable to open and closed position and means for closing and latching said door comprising a bar pivoted on a stationary pivot, a latch fixed on said bar and adapted to engage the door in its closed position, an arm pivoted on said bar and having a latching pawl engageable with the door when the door has been moved to partially closed position, the pivotal connection between said arm and bar being disposed on the opposite side of the bar pivot from the latch fixed thereon, and means carried by said bar and engageable with said arm to release the arm latch when the bar is swung about its pivot in one direction.

5. In combination, a door movable to open and closed position and means for closing and latching said door comprising a bar pivoted on a stationary pivot, a latch fixed on said bar and adapted to engage the door in its closed position, an arm pivoted on said bar and having a latching pawl engageable with the door when the door has been moved to partially closed position, the pivotal connection between said arm and bar being disposed on the opposite side of the bar pivot from the latch fixed thereon, means pivoted to said bar and adapted to retain the latching means in operative position and against accidental displacement, and means carried by said bar and engageable with said arm to release the arm latch when the bar is swung about its pivot in one direction.

6. In combination, a door movable to open and closed position and means for closing and latching said door comprising a bar pivoted on a stationary pivot, a latch fixed on said bar and adapted to engage the door in its closed position, and a member pivoted to said bar and having a latch adapted to engage the door when the door has been swung into partially closed position, the pivotal connection between the member and the bar being disposed on the opposite side of the bar pivot from the latch fixed to said bar.

7. In combination, a door movable to open and closed position and means for closing and latching said door comprising a bar pivoted on a stationary pivot, a latch fixed on said bar and adapted to engage the door in its closed position, and an adjustable member pivoted to said bar and having a latch adapted to engage the door when the door has been swung into partially closed position, the pivotal connection between the member and the bar being disposed on the opposite side of the bar pivot from the latch fixed to said bar.

8. In combination, a door movable to open and closed position and means for closing and latching said door comprising a bar pivoted on a stationary pivot, a latch fixed on said bar and adapted to engage the door in its closed position, an adjustable member pivoted to said bar and having a latch adapted to engage the door when the door has been swung into partially closed position, the pivotal connection between the member and the bar being disposed on the opposite side of the bar pivot from the latch fixed to said bar, and means carried by the bar for engaging and releasing the latch carried by the pivoted member when the door is swung in one direction.

9. In combination, a door movable to open and closed position and means for closing and latching said door comprising a bar pivoted on a stationary pivot, a latch fixed

- on said bar and adapted to engage the door in its closed position, an adjustable member pivoted to said bar and having a latch adapted to engage the door when the door has been swung into partially closed position, the pivotal connection between the member and the bar being disposed on the opposite side of the bar pivot from the latch fixed to said bar, means carried by the bar for engaging and releasing the latch carried by the pivoted member when the bar is swung in one direction, and means carried by said bar for retaining the bar latch and the latch carried by said member in latching position against accidental displacement.
10. In combination, a door movable to open and closed position and means for closing and latching said door comprising a bar pivoted on a stationary pivot, a latch fixed on said bar and adapted to engage the door in its closed position, an adjustable member pivoted to said bar and having a latch adapted to engage the door when the door has been swung into partially closed position, the pivotal connection between the member and the bar being disposed on the opposite side of the bar pivot from the latch fixed to said bar, means carried by the bar for engaging and releasing the latch carried by the pivoted member when the bar is swung in one direction, and gravity actuated means carried by said bar for retaining the bar latch and the latch carried by said member in latching position against accidental displacement.
11. In combination, a structure having a door pivoted thereto, a member secured to said door and extending laterally therefrom and means for closing and latching said door comprising a bar mounted on a fixed pivot, a latch carried by said bar and engageable with the laterally extending member secured to the door when the door is in closed position, and a member pivoted to said bar and having a latching element engageable with said laterally extending member when the door is in partially closed position, the pivotal connection between said member and said bar being disposed on the opposite side of the bar pivot from the latch carried by the bar.
12. In combination, a structure having a door pivoted thereto, a member secured to said door and extending laterally therefrom and means for closing and latching said door comprising a bar mounted on a fixed pivot, a latch carried by said bar and engageable with the laterally extending member secured to the door when the door is in closed position, and an adjustable member pivoted to said bar and having a latching element engageable with said laterally extending member when the door is in partially closed position, the pivotal connection between said member and said bar being

disposed on the opposite side of the bar pivot from the latch carried by the bar.

13. In combination, a structure having a door pivoted thereto, a member secured to said door and extending laterally therefrom and means for closing and latching said door comprising a bar mounted on a fixed pivot, a latch carried by said bar and engageable with the laterally extending member secured to the door when the door is in closed position, a member pivoted to said bar and having a latching element engageable with said laterally extending member when the door is in partially closed position, the pivotal connection between said member and said bar being disposed on the opposite side of the bar pivot from the latch carried by the bar, and means carried by the bar and engageable with the member pivoted to the bar to release the latching member carried by said pivoted member when the bar has been swung in a direction to release the door latching means.

14. In combination, a structure having a door pivoted thereto, a member secured to said door and extending laterally therefrom and means for closing and latching said door comprising a bar mounted on a fixed pivot, a latch carried by said bar and engageable with the laterally extending member secured to the door when the door is in closed position, a member pivoted to said bar and having a latching element engageable with said laterally extending member when the door is in partially closed position, the pivotal connection between said member and said bar being disposed on the opposite side of the bar pivot from the latch carried by the bar, and gravity actuated means pivoted to said bar and engageable beneath the laterally extending member carried by the door for retaining the latching mechanism against accidental release.

15. In combination, a structure having a door pivoted thereto, a member secured to said door and extending laterally therefrom and means for closing and latching said door comprising a bar mounted on a fixed pivot, a latch carried by said bar and engageable with the laterally extending means secured to the door when the door is in closed position, a member pivoted to said bar and having a latching element engageable with said laterally extending member when the door is in partially closed position, the pivotal connection between said member and said bar being disposed on the opposite side of the bar pivot from the latch carried by the bar, gravity actuated means pivoted to said bar and engageable beneath the laterally extending member carried by the door for retaining the latching mechanism against accidental release, and

means carried by the bar and engageable with the member pivoted to the bar to release the latching member carried by said pivoted member when the bar has been 5 swung in a direction to release the door latching means.

16. A door lock comprising a member pivoted on a fixed support, a latch pivoted on said member and adapted to lock the 10 door in partly closed position and a latch fixed on said member and adapted to lock the door in full closed position.

17. A door lock comprising a member pivoted on a fixed support, a latch pivoted 15 on said member and adapted to lock the door in partly closed position and a latch fixed on said member and adapted to lock the door in full closed position, and means for preventing the release of said second 20 latch from the door.

18. A door lock comprising a member pivoted on a fixed support, a latch pivoted on said member and adapted to lock the door in partly closed position and a latch

fixed on said member and adapted to lock 25 the door in full closed position, and means on said member for preventing the release of said second latch from the door.

19. A door lock comprising a member pivoted on a fixed support, a latch pivoted 30 on said member and adapted to lock the door in partly closed position and a latch fixed on said member and adapted to lock the door in full closed position, and means for releasing said first latch from locking 35 position.

20. A door lock comprising a member pivoted on a fixed support, a latch pivoted 40 on said member and adapted to lock the door in partly closed position and a latch fixed on said member and adapted to lock the door in full closed position, means for releasing said first latch from locking position, and means for preventing the release 45 of said second latch from the door.

In witness whereof, I have hereunto set my hand this 2nd day of July, 1924.

THOMAS BRADY.
